MACHINE FOR COMPRESSING
COTTON WADS

Joseph A. Voss, Denver, Colo.

Application October 5, 1934, Serial No. 747,028

14 Claims. (Cl. 18—16)

This invention relates to a machine for compressing absorbent cotton or similar material into relatively hard, self-sustaining wads or cores. It is more particularly designed for compressing a piece of absorbent cotton into a relatively small, tight wad for insertion in the human vagina for catamenial purposes, but is, of course, not limited to this particular use.

The principal object of this invention is to provide a machine for this purpose which will rapidly, continuously, and efficiently form un-compressed cotton pieces into compressed wads.

Another object of the invention is to so construct the device that it will require but a minimum of power; will occupy but a minimum of space; and so that it can be easily and efficiently operated.

A further object is to incorporate with the compressing device, means for folding or convoluting the cotton before the compression thereof.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:—

Fig. 1 is a front elevation of the improved machine.

Fig. 2 is the plan view of the table portion thereof.

Fig. 3 is a detail perspective view illustrating the "tucking" mechanism for feeding the cotton into the compressing chamber.

Fig. 4 is a rear elevation of the machine.

Fig. 5 is an enlarged, longitudinal section through the feed table portion of the machine, taken on the line 5—5, Fig. 2.

Fig. 6 is a cross section taken on the line 6—6, Fig. 2.

Fig. 7 is an enlarged plan view of the compressing portion of the table with the top plate thereof removed.

Fig. 8 is a horizontal section through the final compressing die.

Fig. 9 is a detail end elevation of the final compressing die.

Fig. 10 is a detail cross section taken on the line 10—10, Fig. 2.

Fig. 11 illustrates a typical cotton pad as it appears ready to be fed to the machine.

Fig. 12 illustrates the pad in the compressed or finished condition after passing through the machine.

Fig. 13 is an enlarged detail view of the compressing extremity of the plunger employed in the machine.

The invention comprises a supporting frame 10. The frame 10 supports a feed table 11 extending over a major portion of its length and a compressing plate 12 over the remaining portion. The feed table is formed with a longitudinal channel along its center outlined by two upstanding flanges or ribs 13. The bottom of a channel 15 opens through the bottom of a table 11 between a pair of grooved track members 35. The bottom of the channel is closed, preferably by means of a glass plate 14.

A cross head 15 is arranged to reciprocate along the track members 12 below the glass plate 14. The cross head carries a compressing plunger 16 which is mounted in the cross head against a compression spring 17. Suitable lock nuts 18 are provided, to set the position of the plunger 16 therein. The cross head is reciprocated along its tracks through the medium of a cylindrical drum 19 provided with a projecting cam track 20. A cam follower roll 21 is secured to the cross head 15 and rolls along the edge of the cam track 20, as the drum 19 rotates. The plunger 16 is returned, and the roll 21 is constantly held against the track 20 by means of a tension spring 15 which is connected through a flexible member 16 with the cross head.

The drum 19 is carried on a longitudinal shaft 22 suspended in suitable brackets 23 extending downwardly from the feed table 11. It is rotated from a worm shaft 24 which extends laterally of the machine supported in suitable bearing brackets 25. The worm shaft 24 carries at its middle a worm 26 which meshes with a worm wheel 27 bolted to one extremity of the drum 19. The worm shaft is driven by means of suitable belts 28 from a drive motor 29. The belts 28 transmit the power through a suitable clutch 30 provided with a clutch operating lever 31.

The clutch operating lever is operatively connected with a hand lever 32 convenient to the operator's position. The motion of the hand lever 32 is transmitted through a series of cranks and levers, as illustrated, including a horizontal connecting bar 33. A roller 34 is mounted on the connecting bar 33 so as to bear against one edge of the drum 19. This roller is constantly held 35

against the drum edge by means of a suitable tension spring 36. At one point, the edge of the drum 19 is provided with a depression 37 into which the roller 34 may drop so as to disengage the clutch 30. The operator then operates the hand lever 32 to re-engage the clutch so as to start the rotation of the drum 19. The rotation causes the roller 34 to hold the clutch 30 in engagement until the roller again reaches the depression 37. Thus each operation of the hand lever 32 causes the clutch 30 to engage until the drum 19 has made a complete revolution.

The forward extremity of the plunger 16 passes through an inclined block 38 which is inclined to lead from the surface of the glass plate 14 to a guide block 39. The guide block 39 is provided with an inclined passage 40 which leads to a compressing chamber 41.

The top of the compressing chamber 41 is preferably formed of plate glass 42. The cotton to be compressed is laid on the plate 14 between the ribs 13 and is forced therefrom through the guide block 39 into the compressing chamber 41 by means of a tucking blade 43. This blade is supported from a slide member 44 reciprocating in a guide channel 45. The slide member 44 is rapidly reciprocated through the medium of a connecting rod 46 extending from a crank 47, rotated from an independent motor 48 through the medium of a suitable drive belt 49 and pulleys 50. The rapid reciprocation of the blade 43 causes the cotton to be pushed through the guide block 39 in a series of tucks or convolutions so that it will reach the compressing chamber 41 in a folded or convoluted condition.

The initial compression is imparted to the convoluted cotton by means of a pair of opposed side dies 51, the inner extremities of which contain semi-cylindrical depressions which cooperate with each other to form the convoluted cotton into a tight cylinder as they approach each other. The compressing movement of the side dies 51 is imparted from a pair of compression cams 52 secured on a pair of cam shafts 53. The cam shafts 53 are driven from the worm shaft 24 through the medium of suitable worms and worm wheels 54 and extend along each side of the machine in suitable bearing brackets 55. At each revolution of the camshafts, the two side dies 51 will be caused to approach each other to impart the initial lateral compression to the cotton. The side dies are withdrawn and held in constant contact with the cams 52 by means of compression springs 56 positioned in suitable slots 77 in the dies. The springs 56 are compressed against studs 57 which extend upwardly from the compression plate 12.

When the two side dies close to form the cotton into a cylindrical wad, the plunger 16 advances to force the cylinder into a final compressing die 58 having a cylindrical bore 78 of the exact diameter of the finished product. The compressed wad is prevented from passing initially through the final compression die 58 by a pair of end gates 59 which are caused to approach each other to close the bore in the die 58 by a pair of gate cams 60 which are also secured upon the cam shafts 53. The gates 59 are secured upon the extremities of push rods 61 which terminate in rollers 62 against the cams 60. The rollers are constantly held against the cams by means of compression springs 63 embodied in the push rods 61.

The two end gates 59 are formed with co-acting depressions 64 which when together form a mushroom-like cavity which imparts a mushroom-like

head to the compressed wad. The gates 59 are held tightly against the compression die 58 by means of balls 65 which contact with, and ride upon, inclined surfaces 66 on the gates to force them snugly against the die 58 as they close. The balls 65 receive the pressure of the wad as it is forced against the gates. The pressure of the balls 65 against the gates is adjustable by means of pressure screws 67.

It was found that the great pressure of the cotton against the gates tended to lock them in the closed position so that the action of the gate springs 63 was insufficient to open the gates. This is overcome by placing a bevelled pin 68 in each of the gates between which the wedge-shaped extremity of a gate starting lever 69 passes. The starting lever 69 extends over one of the cam shafts 53 so that it is contacted by a pin 70 during a portion of the revolution to force the bevelled extremity between the bevelled pins 68 and 20 to loosen and pry the gates initially open. The initial movement of the gates releases them from the balls 65, owing to the inclined surfaces 66, so that the springs 63 may readily snap the gates to the open position.

The cam track 20 is so designed that when the clutch roller 34 is in its depression 31, and the clutch 30 is disengaged, the plunger 16 is in the withdrawn position of Fig. 5; the side dies 51 are in the withdrawn position; and the gates 59 are 30 in the open position. The tucking motor 48 and the tucking blade 43 operates continuously.

It is desired to call particular attention to the construction of the extremity of the plunger 16, as shown in detail in Fig. 13. This extremity is 35 reduced in diameter along a gently curved contour, as shown at 79, immediately inside the extreme end. The end itself is substantially the same diameter as the remainder of the plunger 16. A depression 80 is formed in the end face. 40 The edges of this depression are gently rounded into the external surface of the plunger, as illustrated.

The machine may be employed for compressing any style or shape of uncompressed cotton 45 piece into a highly compressed cylindrical wad. Such an uncompressed piece is indicated in Fig. 11, and the typical final compressed product is indicated in Fig. 12. The piece illustrated is formed with a longitudinally stitched withdraw- 50 ing string 81, and when finally compressed carries a relatively soft mushroom-like head 82.

Operation

The operator lays a strip of cotton in the channel, and the blade quickly tucks this cotton into the compressing chamber. The operator then operates the hand lever 32 starting the rotation of the drum 19, and the cam shafts 53. The first movement is made by the plunger 16 which moves 60 forwardly a sufficient distance to push the entire convoluted cotton piece into the compressing chamber. This initial movement is imparted by a point 71 on the cam track. The plunger then recedes and the compression cams 65 52 act to close the two side dies 51. The end gates 59 follow this movement, and close the bore 78. The cam track now ascends so as to force the cross head and the plunger forwardly until the entire cotton wad has been compressed into 70 the final die 58.

At this point the cam track is substantially flat as shown at 72, which allows the plunger to remain against the compressed cotton for an interval of approximately $\frac{1}{5}$ of a revolution. This 75

holds the cotton under compression a sufficient time for it to become set. The track then descends a short interval as shown at 13 so as to release the pressure of the plunger from the wad, 5 at which time, the gates 59 open. The track then ascends to its highest point 14 to force the compressed wad through the open end of the final die to any suitable receiver. The plunger and the cams then return to their initial starting position for the reception of the second wad. When the starting position is reached, the roller 10 34 drops into the depression 37 to release the clutch 30 and stop the machine.

The compressed product as shown in Fig. 12 is formed with an enlarged head 82 caused by the mushroom-like depressions 64 in the end gates 59. The rear of the plug contains a small projecting teat 83 formed by the depression 80 in the extremity of the plunger 16. 15 It is desired to call attention to the shape of the plunger 16. Experiments indicate that the depression 80 allows the pressure on the cotton to be concentrated at the midpoint of the depression 80, and that the depression acts to reduce the pressure at the circumference of the wad. This was found to be necessary to prevent cutting or damaging the withdrawing string 81 at this point. The reduced extremity 19 on the plunger allows ample space about the plunger 20 for the withdrawing string without damaging the latter. It has also been found by experiment, that the pause of the plunger at the high point of compression, caused by the flat length 72 on the cam 20, is a necessity in order to cause 25 the compressed wad to permanently retain its shape until moistened. If the plunger is immediately released after compressing the wad, the latter has a tendency to expand after leaving the final compressing die.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:—

1. A machine for compressing cotton into a compact self-sustaining wad comprising: a receiving plate; a compressing chamber; a compressing die; means for passing said cotton from said receiving plate into said compressing chamber; means for imparting lateral compression to said cotton while in said latter chamber; means for passing said compressed cotton into said compression die and for ejecting said compressed cotton from said compressing die.

2. A machine for compressing cotton into a compact self-sustaining wad comprising: a receiving plate; a compressing chamber; a compressing die; means for passing said cotton from said receiving plate into said compressing chamber; means for imparting lateral compression to said cotton while in said latter chamber; means for passing said compressed cotton into said compression die and for ejecting said compressed cotton from said compressing die; and means for holding said cotton from ejection for a time interval.

3. A machine for compressing cotton into a compact self-sustaining wad comprising: a receiving plate; a compressing chamber; a compressing die; an end gate closing the discharge of said compression die; means for forcing the cot-

ton from the compressing chamber into the compression die; and means for opening said end gate at a predetermined time to allow ejection of said cotton from said compressing die.

4. A machine for compressing cotton into a compact self-sustaining wad comprising: a receiving plate; a compressing chamber; a compressing die; side dies positioned to contract said compression chamber to impart initial compression to said cotton; a plunger for forcing the initially compressed cotton into said compressing die; and a tucking member acting to pass the uncompressed cotton into said compressing chamber in a convoluted or folded condition.

5. A machine for compressing cotton into a relatively tight self-sustaining wad comprising: a plate for receiving said cotton; an inclined block for receiving the cotton from said plate; a guide block for receiving the cotton from said inclined block; a compressing chamber for receiving the cotton from said guide block; a compressing die for receiving the cotton from said compressing chamber; laterally moving compression members in said compressing chamber; and a longitudinally reciprocating plunger for passing the cotton through said guide block and through said compressing chamber into said compressing die.

6. A machine for compressing cotton into a relatively tight self-sustaining wad comprising: a plate for receiving said cotton; an inclined block for receiving the cotton from said plate; a guide block for receiving the cotton from said inclined block; a compressing chamber for receiving the cotton from said guide block; a compressing die for receiving the cotton from said compressing chamber; laterally moving compression members in said compressing chamber; a longitudinally reciprocating plunger for passing the cotton through said guide block and through said compressing chamber into said compressing die, said plunger passing through said inclined block; and end gates for closing said compressing die at predetermined times.

7. A machine for compressing cotton strips into compact self-sustaining wads comprising: a receiving plate; a plunger reciprocating below said plate; a passage extending from said plate to a position ahead of said plunger; a compression chamber; means for imparting lateral compression in said compressing chamber; and means for passing the cotton strip from said receiving plate into said passage so that said plunger may force it into said compressing chamber.

8. A machine for compressing cotton strips into compact self-sustaining wads comprising: a receiving plate; a plunger reciprocating below said plate; a passage extending from said plate to a position ahead of said plunger; a compression chamber; means for imparting lateral compression in said compressing chamber; and means for passing the cotton strip from said receiving plate into said passage so that said plunger may force it into said compressing chamber; and a final forming die positioned to receive the compressed cotton from said compressing chamber.

9. A machine for compressing cotton strips into compact self-sustaining wads comprising: a receiving plate; a plunger reciprocating below said plate; a passage extending from said plate to a position ahead of said plunger; a compression chamber; means for imparting lateral compression in said compressing chamber; a tucking blade positioned above said receiving plate; and means for imparting a relatively rapid reciprocating movement to said blade to cause the latter to tuck

said strip into said passage ahead of said plunger.
10. A machine for compressing cotton strips into compact self-sustaining wads comprising: a pair of relatively flat side dies; a bottom plate 5 supporting said dies; a top plate extending over said dies so as to form a compression chamber therebetween; a passage leading to said compression chamber; a final forming die having a bore leading from said compression chamber; means 10 for feeding the strip into the passage; a plunger for forcing the fed strip between said side dies; means for causing said side dies to approach each other to compress the cotton to a wad of a size to enter said bore; and means for imparting a 15 relatively long stroke to said plunger for forcing said wad into said bore.

11. A machine for compressing cotton strips into compact self-sustaining wads comprising: a pair of relatively flat, side dies; a bottom plate 20 extending supporting said dies; a top plate extending over said dies so as to form a compression chamber therebetween; a passage leading to said compression chamber; a final forming die having a bore leading from said compression 25 chamber; means for feeding the strip into the passage; a plunger for forcing the fed strip between said side dies; means for causing said side dies to approach each other to compress the cotton to a wad of a size to enter said bore; means 30 for imparting a relatively long stroke to said plunger for forcing said wad into said bore; a pair of gate members closing the discharge extremity of said bore; and means for withdrawing said gate members to allow said wad to be discharged. 35

12. A machine for compressing cotton strips

into compact self-sustaining wads comprising: a table; a longitudinal channel on the top of said table; a plunger reciprocating below said channel; a passage leading from said channel to the head of said plunger; means for passing said strip from said channel into said passage; a compression chamber, said plunger being positioned to pass said strip from said passage into said compression chamber; side dies in said latter chamber for imparting an initial lateral compression to said 10 strip; a forming die leading from said compression chamber; and means for imparting a relatively long stroke to said plunger at a predetermined time to force the initially compressed cotton from said compression chamber into said 15 forming die.

13. Means for feeding a strip of cotton into the compression chamber of a compressing device comprising: a reciprocating member; a blade supported at its one extremity by said reciprocating member and contacting said cotton at its other extremity; and means for reciprocating said reciprocating member so as to cause said blade to tuck said cotton and force the latter into said compressing device. 20

14. In a machine for compressing cotton into a compressing die having a bore extending entirely therethrough, two slidably mounted end gates positioned to close one extremity of said bore at predetermined times, said gates contacting with each 30 other substantially on the center line of said bore; a starting element arranged to initially move said gates to break the latter loose from said cotton; and means for opening said gates after the initial movement has been accomplished. 35

JOSEPH A. VOSS.
